UNITED STATES PATENT OFFICE.

JOHN JOHNSON, OF PERRYVILLE, MISSOURI, ASSIGNOR OF ONE-HALF TO THOMAS A. SON, OF BONNE TERRE, MISSOURI.

RIM-TOOL.

1,201,190.

Specification of Letters Patent. Patented Oct. 10, 1916.

Application filed July 27, 1916. Serial No. 111,718.

To all whom it may concern:

Be it known that I, JOHN JOHNSON, a citizen of the United States, residing at Perryville, in the county of Perry and State 5 of Missouri, have invented certain new and useful Improvements in Rim-Tools; and I do declare the following to be a full, clear, and exact description of the invention, such as will enable others skilled in the art to 10 which it appertains to make and use the same.

My invention relates to improvements in tools for contracting and expanding common types of split rims which are detachably secured to automobile wheels, the object being to provide a simple and inexpensive tool of this class by whose use the rim may be easily contracted to remove and expanded to replace the tire.

20 With this general object in view, the invention resides in certain specific features of construction to be hereinafter fully described and claimed, the descriptive matter being supplemented by the accompanying 25 drawings which constitute a part of this application and in which:

Figure 1 is a side elevation of the improved tool applied to a rim; Fig. 2 is a similar view showing the manner in which 30 said rim is contracted by the tool; Fig. 3 is a transverse section on the line 3—3 of Fig. 1 with the parts in position for contracting the rim; Fig. 4 is a fragmentary view similar to Fig. 3 showing the manner 35 in which the pointed end of the operating rod bears against the rim when expanding the latter; Fig. 5 is a horizontal section on the plane of the line 5—5, of Fig. 1; Fig. 6 is a vertical section taken on the plane of the 40 line 6—6 of Fig. 3; Fig. 7 is a sectional view on the plane indicated by the line 7—7 of Fig. 1; and Fig. 8 is a detail section of Fig. 7 on the plane of the line 8—8.

In specifically describing the construction 45 shown in the drawings above briefly described, similar characters will be employed to designate corresponding parts throughout the several views and reference will be herein made to the numerous elements by their 50 respective indices. To this end, the numeral 1 designates a common type of automobile rim whose ends meet at the point 2 and are adapted to be separated and moved inwardly to contract the rim sufficiently to permit the 55 tire 3 to be removed or replaced as occasion

may demand. For contracting the rim and again expanding the same, the improved tool 4 is provided.

The tool 4 comprises a C-clamp 5 adapted to be clamped by means of its set screw 6 to the rim 1 opposite the point 2, the yoke of said clamp having formed therein a circular opening 7 in which one end of a rod 8 is rotatably mounted, this end of said rod being pointed as shown at 9 and having a stop collar 10 which bears against the aforesaid yoke of the clamp 5. The other end of the rod 8 is threaded into a sleeve 11 having oppositely projecting upwardly diverging ears 12 and links 13 are pivoted to ears 14 on a pair of C-clamps 15, the latter having set screws 16 by means of which they are adapted to be secured to the opposite ends of the rim 1.

For the purpose of rotating the rod 8 any 75 suitable means may be provided but the center of said rod is preferably enlarged as shown at 17 and a forked handle 18 is pivoted to said enlargement.

When the improved tool is used for contracting a rim to permit removal of a tire therefrom or application of another thereto, it is applied as shown in Fig. 1. The two ends of the rim will now be separated by a screw driver or the like to permit one end 80 to move inwardly beyond the other, whereupon the rod 8 will be rotated and will thus draw both ends of the rim inwardly toward the center of the latter, thereby decreasing the size of said rim the required amount. 85 After applying a new tire to the rim, rotation of the screw in the opposite direction will force the two ends of the rim back to their normal positions and during this operation, the pointed inner end 9 of the rod 90 8 will bear against the rim and will thus serve as an effective thrust bearing with very little friction.

From the foregoing taken in connection 100 with the accompanying drawings, the construction, manner of operation and advantages of the improved tool will be readily understood without requiring a more extended explanation but in conclusion I will state that although the tool as manufactured 105 is constructed as shown and described, numerous minor changes may be resorted to as occasion may demand.

I claim:

A rim contracting and expanding tool 110

comprising a C-clamp to be secured on a split rim opposite the meeting ends thereof, the yoke of said clamp having formed therein a circular opening, a rod having one end 5 rotatably mounted in said opening and having this end brought to a point to serve as a thrust bearing to contact with the rim, a stop collar secured on said end of the rod to bear against the inner side of said yoke of the clamp, a sleeve in which the other end 10 of the rod is threaded, a pair of links pivoted to said sleeve at one end, a pair of C-

clamps to which the other ends of said links are pivoted, said clamps being adapted to be secured on the meeting ends of the rim, 15 and means for rotating the aforesaid rod.

In testimony whereof I have hereunto set my hand in the presence of two subscribing witnesses.

JOHN JOHNSON.

Witnesses:

SYLVESTER ZAHNER,
JOHN F. GEILE.
